CLAIM

The ornamental design for a five-way buckle, as shown and described.

DESCRIPTION

FIG. 1 is a perspective view of a five-way buckle showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view thereof, taken from encircled portion 9 in FIG. 1;

FIG. 10 is another enlarged view thereof, taken from encircled portion 10 in FIG. 1;

FIG. 11 is an enlarged view thereof, taken from encircled portion 11 in FIG. 2;

FIG. 12 is an enlarged view thereof, taken from encircled portion 12 in FIG. 3;

FIG. 13 is an enlarged view thereof, taken from encircled portion 13 in FIG. 4;

FIG. 14 is an enlarged view thereof, taken from encircled portion 14 in FIG. 5; and,

FIG. 15 is an enlarged view thereof, taken from encircled portion 15 in FIG. 8.

The broken lines shown on the drawings depict portions of the five-way buckle that form no part of the claimed design. The dot-dash broken lines depict the bounds of the claim and form no part of the claimed design.

1 Claim, 15 Drawing Sheets
